LOUIS STEINBERGER, OF BROOKLYN, NEW YORK.

INSULATING-SUPPORT FOR HIGH-TENSION CONDUCTORS.

1,160,544.

Specification of Letters Patent. Patented Nov. 16, 1915.

Application filed July 3, 1911. Serial No. 636,598.

To all whom it may concern:

Be it known that I, LOUIS STEINBERGER, a citizen of the United States, and a resident of the city of New York, borough of Brooklyn, in the county of Kings and State of New York, have invented a new and Improved Insulating-Support for High-Tension Conductors, of which the following is a full, clear, and exact description.

10 My invention relates to an insulating support admitting of general use but more particularly adapted for high tension lines.

15 My invention comprehends the employment of rod type insulators suspended from a cross arm or other support for supporting the line, and also comprehends the combination (when desired or required) of rod type and disk or hood type insulators suspended from a cross arm or other support, for supporting the line, the arrangement of the insulators being such as to promote a maximum of strength and durability combined with a certain amount of flexibility in supporting the line.

25 My invention further comprehends means for protecting the insulating members or parts thereof as far as practicable from moisture, thereby enhancing the value of the insulation.

30 In addition, my system comprehends such an arrangement of parts as will distribute the mechanical strains to the best advantage and tend to prevent the line from falling to the ground or being unduly lowered 35 in case of the destruction of one or more of the various parts employed.

Among the many purposes sought to be accomplished by aid of my invention are the following:—I. To provide a clamp or analogous supporting member for sustaining the line and to connect with this clamp or analogous member a plurality of independent insulating supports, one acting in a different manner from the other. II. To so dispose 40 a number of flexible insulating members and a number of rigid insulating members that while all of the members contribute to support the line the rigidity of the rigid insulating members does not interfere with 45 the flexibility of the flexible insulating members, and vice versa, the flexibility of the flexible members does not interfere with the rigidity of the rigid members. III. To provide 50 a rain-shield of such form and so positioned that in addition to shedding mois-

ture, said rain-shield serves as a brace for preventing breakage of various parts. IV. To promote accessibility to the various parts and to enable one part to be removed temporarily without disabling the system 60 as a whole. V. To render the rain-shield detachable so that it can be dispensed with whenever desired. VI. To so dispose the rod type insulators and the chain type insulators that as far as practicable heavy strains 65 in particular directions are borne by particular parts. VII. To provide a rod type strain insulator which can be used as an independent unit, and in any relation where a strain insulator is usually employed. 70 VIII. To provide a removable rain shield for horizontally disposed longitudinal insulators. IX. To provide a form of flexible suspension insulator capable of service as a dead-ending for conductors.

75 Reference is made to the accompanying drawings forming a part of this specification, and in which like numbers indicate like parts.

Figure 1 is a perspective showing my system as used upon a number of associated lines, some of the rain-shields being in this instance removed for the sake of clearness; Fig. 2 is a detail showing a fragmentary section through a group of insulators used 80 for supporting a line and showing the manner in which the rain shield is mounted; Fig. 3 is a detail showing a chain of disk-type insulators, each provided with a hook, this chain as a whole constituting one of the 85 flexible insulating members; Fig. 4 is a detail showing partly in side elevation and partly in section the end of one of the supporting beams and various parts associated therewith and also showing one of the rod-type insulators connected with said end of 90 said supporting beam; Fig. 5 is a detail showing the supporting clamp for sustaining the line, said line appearing in cross section; Fig. 6 is a detail showing the manner 95 of mounting the cross beam upon the supporting towers; and Fig. 7 is a detail showing the manner in which the brackets used for supporting the rain sheds are prevented 100 from turning on their supports.

105 The various lines to be supported are shown at 7 and may be wires, cables or conductors of any desired form. Each line 7 is engaged at intervals by clamps 8 preferably of the form shown in Fig. 5. Each clamp 8 110

is provided at its bottom with a hook portion 9 and with a jaw 10 for engaging the line. The jaw 10 is held in position by aid of a bolt 11 and nut 12. By removing the 5 nut the jaw 10 may be disengaged from the line and the latter easily removed or replaced. For purposes of adjustment the wire need not be disengaged entirely from the clamp as the bolt 11 may be loosened by 10 turning the nut 12 and the clamp can be slipped along the line to any desired extent, and when properly adjusted may be merely tightened by turning the nut. The clamp 8 is provided with ears 13, 14, preferably four 15 in number and disposed at right angles relatively to each other. The ears 14 are in this instance forked. Each ear is provided with a hole 15. As may be readily understood from Fig. 5, the ears 13, 14 are somewhat 20 independent of each other and need not all be in use at the same time. In some instances (see right of Fig. 1) only the ears 13 are in active service, the ears 14 being idle; in the other instance (see left of Fig. 1) all four 25 of the ears being in use at the same time. The number of ears to be used is not always the same, and varies with the nature of the work for which the clamp is employed.

Where my system is used as indicated in 30 Fig. 2, I employ a number of rod type insulators 16 (see Fig. 4), each made of a single integral rod provided with successive portions 17, each of substantially frusto-conical form, the portions of greatest diameter of 35 each section, where it joins the next successive section presenting practically an annular shoulder 18. The rod type insulators are usually arranged in pairs, the insulators of each pair inclining toward each other at 40 their lower ends and connected with the adjacent ears 14 of the clamp 8 by aid of eyes 19, having holes 22^a, and pivot pins 20. Each eye 19 is integral with a head 21 which is secured directly upon the lower end of the 45 corresponding rod type insulator. The upper end of each rod type insulator is similarly provided with a head 22. The construction of these heads may be understood by reference to Fig. 4. They are preferably 50 formed of metal and are each substantially frusto-conical in shape, and the adjacent ends of the insulator are provided with frusto-conical depressions 22^b and 22^c into 55 which the heads fit neatly, though they do not quite reach the bottoms. Two gaskets 22^e and 22^f are mounted within the respective openings 22^b and 22^c and engage the adjacent portions of the heads 21 and 22. A rod 22^g, of a tough, strong insulating material, is provided with a threaded end 22^h which extends into the head 22, the latter being threaded for this purpose. The rod 22^g also extends into the head 21 and is engaged by a rivet 22^k which extends diametrically through both the head 21 and the ad-

jacent portion of the head 22. The rod type insulator is, by virtue of the rod 22^g, and the two insulator heads 21 and 22, made very strong and it is rendered still stronger by virtue of the strength of the insulating material of which it is mainly composed and which serves in a measure to brace the rod 22^g and the metallic heads 21 and 22. 70

It will be apparent that the gaskets 22^e and 22^f serve as cushions, and, when the 75 heads 21 and 22 are pressed thereagainst, they serve to impart a tensile strain to the strain member G and a corresponding compression strain to the body of the insulator, so that these parts are held rigid without undue strain upon the side walls of the pockets. 80 By the time that the side surface of the heads come into close contact with the side walls of the pockets a considerable pressure is exerted upon the gaskets or cushions. 85 Likelihood of injury to the material forming the walls of the pockets is thus avoided. The gaskets or cushions of course also serve to maintain the several parts against rattling or the like such as may naturally follow unequal expansion or contraction of the different insulating materials entering into the construction of the body and tension rod. 90

The head 22 of the upper end of the rod-type insulator, is provided with an eye 24 integral with it. The eye 24 is supported by a clevis 25, the upper portion of the latter being properly formed to fit the under side of a pin 31 as hereinafter described. 95

At 26 is a bearing which fits upon the upper side of the pin 31 and mates the upper end of the clevis. The bearing 26 and the upper end of the clevis are provided with lugs 27, and extending through these 100 lugs are bolts 28.

A rod-type insulator 29 is provided with annular depressions or grooves 30 and with comparatively sharp annular surfaces 30^a. This is for the purpose of facilitating the 110 dripping of moisture from the under side of the rod-type insulator, should any such moisture happen to reach the rod-type insulator. This rod-type insulator 29 is merely a straight bar disposed horizontally 115 and supported at its middle by a cross beam 40, as hereinafter described.

The pin 31 is provided upon its upper surface with a facet 31^a extending inwardly for a little distance from the outer end of 120 the pin. The pin 31, for a little more than half of its length, is embedded within the material of the rod-type insulator 29 and is co-axial with this rod-type insulator, a portion of the pin, however, being bare and 125 extending directly outward from the center of the rod-type insulator. A supporting bracket 33 is provided at its bottom with a massive eye 32 which fits neatly upon the pin 31. The bracket 33 is also provided 130

with an extending portion 34 integral with it. The eye 32 is provided with an opening into which the protruding portion of the pin 31 neatly fits, the upper surface of the opening being flat, or in other words, mating the facet 31^a, as will be understood from Fig. 7. The pin 31 is further provided with a reduced threaded portion 31^b. The bracket 33 is, by virtue of the fit of the eye 32 upon the pin 31, effectively prevented from turning. It is still further prevented from turning by pressure of a nut 35 and that of a lock nut 36, said nuts being fitted upon the reduced threaded portion 31^b of a supporting pin 31. A rain shield 37, having generally the form of an inverted trough of uniform width, is disposed just above the rod-type insulator 29 and parallel with the same. The rain shield is provided with ends 38 which are beveled and sloped obliquely downward, extending some distance beyond the adjacent ends of the rod-type insulator 29 and covering various metallic parts carried by said 25 ends. There are two of the brackets 33 for supporting each rain shield 37, and secured thereto by bolts 39.

Each rod-type insulator 29 is engaged by a strap 41 having generally a U-shaped 30 form in cross section and held upon the upper side of the cross beam 40 by aid of bolts 42. The cross beam 40 is substantially T-shaped in cross section. Bolts 43 extend through the lower portion of the cross beam 35 and support the composite flexible insulating members or chain or insulators shown in detail in Fig. 3. Each of these chains is made up of separate units 44, each unit comprising a disk 45 and a hood 46 of insulating material. Each unit further comprises eyes 47, 48 of metal, the two eyes of each unit being insulated from each other. The cross beams 40 are mounted upon supporting towers 49, each made up 40 principally of A frame 50, the supporting beams 40 being held in position by aid of bolts 48^a.

As above stated, the rain shields 37 are detachable and may be removed by taking 50 out the bolts 39. In some instances, it may be preferable to discard some of the rain shields (see Fig. 1), but in doing this no structural change is necessary. If desired the brackets 33 may be kept permanently in 55 position upon the ends of the rod-type insulator 29, so that the rain shield 37 may be added whenever desired by the operator. Since, however, the brackets 33, like the rain shields are removable, these brackets 60 can be taken off altogether and the nuts 35, 36 tightened up accordingly.

My invention is used as follows: In instances where the line requires considerable bracing, as shown for instance at the left of 65 Fig. 1 where the lines are bent into curves,

I prefer to employ, as a group for supporting the line at a single point, one pair of rod-type insulators 16 and one pair of flexible or chain insulators, the flexible insulators extending in a direction crossing the 70 length of the line. When, however, the line is not subjected to any considerable strain in a direction crossing the length of the line, the rod-type insulators only need be employed.

Since all of the advantages peculiar to my system may be employed in the same structure, as indicated in Fig. 2, this figure may be considered as a representation of my invention in its entirety. It should be understood, however, that I may, and frequently do, discard various parts shown in this figure, and that various mechanical features shown in this figure may be employed independently of each other.

Suppose now that, as shown in Fig. 2, and also in Fig. 1 at the left, the parts are assembled as shown: The rain shield, being detachable, may be laid aside if desired, as indicated at the left of Fig. 1. If the lateral displacement of one of the lines 7 due to the curvature of said line or to any other cause is very great so that the strain of the line is exerted altogether upon one of the chains to the exclusion of the other, it may 90 not be necessary to use but one of the chains. In this event, the chain employed should, of course, be placed upon that side of the line where it will encounter and consequently oppose, the lateral strain of the 95 100 wire.

As is apparent from the foregoing description, my system can be employed in quite a number of different ways and may be used for supporting lines which are subjected to peculiar strains or which are not subjected to any strains except those which are always to be expected.

Suppose now that the system, in its complete form, is employed, and that the mechanism shown in Fig. 2 supports the line 7 at a particular point. If the operator finds that the line 7 is pulling considerably harder upon one of the rod-type insulators 16 than upon its mating rod-type insulator, he can, 110 by loosening the clamp 8, adjust the line as above described. Suppose now that owing to a strong wind pressure or to some other momentary or temporary cause, the line 7 is pulled sharply to the right, according to 115 Fig. 2. The rod-type insulator 16 at the left is now subjected to a tensile strain whereas the rod-type insulator 16 at the right is subjected to a compression strain. Most insulating materials, including Electrose, will 120 stand greater compression strain than tensile strain, and consequently the rod-type insulator 16 at the right can, because of its position and the character of the strain thrown upon it, resist a pressure which is 125 130

enormous. Not only that, but the rod-type insulator 16 at the left, by pulling to the left, sustains a part of the strain. This, however, is not the only distribution of strains present. The rod-type insulator 29 is braced by the rain shield 37 and consequently these two parts act in much the same manner as a single rod-type insulator of large dimensions and possessing great strength. It will be noted that when either one of the rod-type insulators 16 is subjected to a compression strain, or to a tensile strain as the case may be, this strain is practically in the general direction of the axis of the rod-type insulator thus affected. For the purpose of allowing the free transmission of the various strains to which the rod-type insulators are subjected, the chain type insulators are free to swing to the right or left as will be understood from Fig. 2.

It may be here noted that in the construction of transmission systems employing towers to which insulators are attached for supporting conductors from the towers, especially in the high tension transmission, it is customary to employ flexible suspension insulators depending from most of the towers, such insulators having the conductor attached to their lower end. At numerous points in the length of the system other towers must be employed to which the conductor may be dead-ended so as to be fixed against excessive longitudinal movement, and jumper connections, and the like employed for continuing the service. These latter towers must obviously be lower than the other towers, that is, they must have portions to which the conductor is to be attached, lowered into the horizontal plane of the conductor. Strain insulators are attached to these portions by one end, and the conductor attached to the strain insulators at the other end, so that the strain insulators extend substantially horizontally in a well known manner.

By the use of my invention I have avoided the necessity for providing towers of different heights for dead-ending, jumper connection, or other like purposes. Any one of my insulators may be employed as a dead-ending. The structure is entirely inflexible, in the direction of the length of the conductor, except as the parts, especially the horizontally disposed member 29 will bend and give under stress, and, being clamped rigidly upon the conductor is fully capable of sustaining the strains from the conductor to retain it against appreciable longitudinal movement as has been above clearly set forth. The structure, is, however, susceptible to a desirable flexibility transversely of the length of the conductor. Jumper connections, therefore, are entirely dispensed with, for their only function, or at least their most important function, is to

70 permit the use of the common horizontal dead ending insulators, and since these are done away with there remains no need of the jumper connection.

The conductor is supported beneath the insulator structure and in case of breakage, the conductor would fall free of the tower, thus saving the tower and insulator from possible destruction and avoiding short circuit to the ground.

75 Suppose now that the line 7 is subjected to a powerful lateral pressure, as for instance one due to a wind blowing directly across it. In this event, all of the strain is borne by one of the chain type-insulators, 80 and as the chain type insulators have flexibility, the line can yield slightly and move in a direction lateral to the length of the line. The natural sagging of the chain type insulators will afford ample lateral movement of the line without requirement for 85 purposely providing a slack. The strength of the line is thus greatly conserved as the line is not nearly as apt to break under pressure of the wind or of accumulation of snow 90 or ice if free to yield slightly and move in the direction in which the pressure against it is applied. Moreover, the flexibility given to a line by my system facilitates the bending and shaking of the line when loaded 95 with snow or ice and thus facilitates the automatic removal of said snow or ice. Indeed, by having the line free to swing 100 slightly in the general direction of its length, moisture is shed more readily from the line. 105 This is because the movements of the line, especially under vicissitude of wind pressure from various directions and of different intensities, causes the line to shake off rain-drops and to become dry. The lost play between the member 8 and the lower ends of the rod-type insulators 16, and in the eyes 24 at the upper ends of the rod-type insulators 16, increase the possible longitudinal movement of the line wire in addition to 110 that afforded by the flexing of the horizontal rod-type insulator 29. The whole movement is only slight, and while it is sufficient to absorb sudden shocks, it is, however, not enough to interfere with the use of the structure as a dead-ending for a conductor. It 115 will be observed that the construction shown and described, while promoting sufficient flexibility for the purposes stated, has nevertheless a considerable degree of rigidity, 120 which is but manifested after the limit of flexibility is reached. The two rod-type insulators 16 are so disposed and connected that the two chain type-insulators serve as guys for preventing movements of the line 125 beyond the limits of flexibility allowed by the chain-type insulators. Moreover, heavy strains such as are always expected from the weight of the line and the wind pressure upon it, are, as far as practicable, borne by 130

distinct parts of the insulator mechanism. For instance, a direct lineal pull upon the line 7 is sustained by a compression strain in one of the rod-type insulators and a tensile strain in another rod-type insulator, these two parts sustaining all or nearly all of the particular strain in question. Again, if there be a strong side wind, practically all of its pressure is resisted by a distinct

10 part, to wit, one of the chain type insulators. Here is a principle now well recognized in many arts, for instance, in the construction of heavy ordnance and in architecture. This principle is to throw all excessively heavy 15 strains upon distinct parts, built for the purpose of resisting them.

As above stated, I do not limit myself to the use of a structure comprising all of the various parts above described. Neither do

20 I limit myself to the use of any particular material for the construction of the insulating members though for this purpose I preferably employ a substance known in this art as "Electrose." Nor do I limit myself 25 to the precise form or part of any part as shown, nor to any particular combination of the parts herein shown and described, the scope of my invention being commensurate with the scope of my claims.

30 Having thus described my invention, I claim as new and desire to secure by Letters Patent:—

1. An insulating support, comprising a pair of rod-type insulators for supporting 35 a strain in the general direction of their length, a pair of chain-type insulators extending in a different direction from that of said rod-type insulators for supporting a strain in the general direction of their own 40 length, and means for connecting a conductor to said rod-type insulators and to said chain-type insulators, said means serving also to connect all of said insulators together, and the chain type insulators permitting a limited movement of the conductor in one direction.

2. In an insulating support, the combination 45 with a cross beam, and a stationary rod-type insulator disposed horizontally and supported by said cross beam, of rod-type insulators suspended from said first-mentioned rod-type insulator and inclined downwardly toward each other; a conductor supporting member carried by said last mentioned rod-type insulators and located at the lower ends thereof, and guying means for said conductor supporting member, said guying means allowing the supporting member a limited play.

3. An insulating support comprising a horizontally disposed base member, a rod-type insulator extending across said base member and being supported thereby, a pair 55 of rod-type insulators connected to swing one from each of the ends of said first men-

tioned rod-type insulator, and being inclined downwardly toward each other, a conductor supporting member connected to the lower ends of said inclined insulators, a pair of chain-type insulators connected to said conductor supporting member and extending at different angles therefrom into supported engagement with said base member, so as to serve as guys permitting a limited swinging of said conductor supporting member.

4. An insulating support comprising a horizontally disposed rod type insulator, means for supporting the same, a pair of separately formed elongated insulators suspended one from each end of said first mentioned insulator being inclined toward each other, so that their lower ends are in relatively close proximity, and a line supporting member connecting said juxtaposed lower ends.

5. An insulating support comprising a substantially horizontally disposed longitudinal insulator, means for supporting the same, a rain shield above said insulator, a plurality of other insulators adapted to support a conductor, means connecting said plurality of insulators independently with said first mentioned insulator, and said connecting means serving to support said rain shield.

6. In a suspension insulator, the combination with a suitable support, of a four-point suspension for a conductor, comprising a pair of rigid, opposed, convergent, rod type insulating members, and a pair of convergent, chain-type insulating members, and a rod-type insulating member for connecting one of said pairs of insulating members to said support.

7. An insulating support comprising a rod-type insulator, a plurality of chain-type insulators, and means connected to said insulators for supporting a conductor, said rod-type insulator being arranged to receive a strain in the direction of its length to retain the conductor against appreciable longitudinal movement in one direction, and said chain-type insulators extending from said conductor supporting means in opposite directions transversely of the longitudinal plane of the conductor and serving to limit movement of the conductor transversely of its length.

8. An insulating support, comprising a rod-type insulator disposed horizontally and supported at its approximate middle, said rod-type insulator being provided at its ends with metallic pins extending substantially axially therefrom, brackets mounted one upon each of said pins and extending upwardly therefrom adapted for supporting a protective member above said rod-type insulator, and a pair of rod-type line supporting insulators pivotally connected one to each of said metallic pins, substantially as described.

9. In an insulating support, the combination with a horizontally disposed supporting beam having a central reinforcing rib extending downwardly therefrom; of a horizontally disposed insulating member extending across said supporting beam having its ends spaced from the sides thereof; insulators connected to said first mentioned insulating member and inclining toward each other beneath said supporting beam; means connecting the lower ends of said inclined insulators; and other insulating members connected with said means and being also connected with the reinforcing rib of said horizontal supporting member, substantially as described.

10. In an insulating support, the combination of a clamp for engaging a line wire and being provided with two pairs of ears arranged in substantially right angular relation; rod-type insulators connected with one pair of said ears; and chain-type insulators connected with the other pair of said ears and extending substantially at right angles to said rod type insulators, said rod type insulators serving to prevent movement of said line wire in all but one plane, and said chain-type insulators serving to limit the movement of said line wire in that one plane.

11. In an insulating structure for supporting a line wire, the combination of a suitable support, a pair of elongated insulator members spaced apart at their upper ends and depending from said support, said elongated insulator members approaching each other at their lower ends, means connecting together the lower ends of said elongated insulator members and being connected with the line wire, both said elongated insulator members and said line wire lying in a common vertical plane, and guying means therefor transverse to the line wire.

12. In an insulating structure, the combination with a suitable support, of a rod type insulator rigidly connected to said support and projecting laterally therefrom, and other insulator members connected to the ends of said rod type insulator having means associated therewith for the attachment of a line wire.

13. In an insulating structure, the combination with a suitable support, of a rod type insulator rigidly connected with said support and projecting laterally therefrom, a second rod type insulator connected to the outer end of the first rod type insulator, means for connecting a conductor to said second rod type insulator, and guying means for said second rod type insulator.

14. In an insulating structure, the combination with a suitable support, of a rod type insulator rigidly connected to said support and projecting laterally therefrom, a second rod type insulator connected to swing from the outer end of the first rod type in-

sulator, means extending from the outer end portion of said second rod type insulator and engaging said first rod type insulator to retain the second rod type insulator against swinging movement in one direction, and means for attaching a conductor to the outer end of the second rod type insulator.

15. An insulating support, and a protecting member therefor, said insulating support comprising an insulating member, and a plurality of other insulating members, a connecting member connecting said last mentioned insulating members together, said connecting member having means for the attachment of a conductor, connecting means connecting said last mentioned insulating members with said first mentioned insulating member, and said connecting means serving to support said protective member.

16. An insulating support comprising a rod type insulating member supported intermediate its length, a plurality of other insulating members connected to opposite ends of said first insulating member, and conductor attaching means supported from said last mentioned insulating members collectively.

17. An insulating support comprising an elongated insulating member supported at its approximate middle, a plurality of other insulating members connected to said first insulating member at points spaced from the point of support of said first insulating member, and conductor attaching means supported from said last mentioned insulating members collectively.

18. An insulating support comprising an insulating member, a plurality of other insulating members connected to said first insulating member, conductor attaching means supported from said last mentioned insulating members collectively, and guying means for said conductor attaching means.

19. A rod-type insulator comprising a body portion, a strain member extending through said body portion having a head arranged at one end thereof, said head being movable in one direction to dispose one portion of the surface thereof directly in engagement with the surface of said body, and a cushion member arranged between another portion of the surface of said head and the surface of said body in a position to be compressed when the first mentioned surface of said head has been moved into engagement with the surface portion of said body, for the purpose set forth.

20. A rod-type insulator comprising a body portion having a frusto-conically shaped pocket formed in one end thereof, a strain member extending through said body portion having a frusto-conically shaped head at one end thereof received in said pocket in close engagement with the conical walls of said pocket, and a cushion member

compressed between the inner end surface of said head and the bottom wall of said pocket.

21. A rod-type insulator comprising an elongated body portion of insulating material having a bore extending longitudinally therethrough, said bore being enlarged at its outer ends to form outwardly flaring frusto-conically shaped pockets at the outer ends of said body portion, a strain member extending through said bore, having frusto-conically shaped heads at its opposite ends, one of said heads being adjustable longitudinally of said strain member to dispose the conical exterior surface of both of said heads in close contact with the conical walls of the respective pockets, and cushion means within one of said pockets compressed between the inner end surface of the adjacent head and the bottom wall of said pocket.

22. An insulating support comprising a rod type insulator, other insulators connected at opposite ends thereof for the attachment of a conductor thereto, a rain shield, and means for retaining said other insulators connected to said rod type insulator, said means also serving to retain said rain shield.

23. An insulating support comprising a rod

type insulator, other insulators connected at opposite ends thereof for the attachment of a conductor thereto, a rain shield, and means for retaining said other insulators connected to said rod type insulator, said means also serving to retain said rain shield and being adapted to permit detachment of the rain shield without detachment of said other insulators.

24. In a device of the class described, a supporting member of T cross section, means for holding said supporting member with the web thereof depending in a vertical plane, a rod type insulator resting upon the upper surface of the cross of the T and having its opposite ends extending beyond the opposite ends of the cross of the T, other insulators carried by the projecting portions of said rod type insulator and by the depending web of the T, and means supported collectively by said other insulators for supporting a conductor.

In testimony whereof I have signed my name to this specification in the presence of two subscribing witnesses.

LOUIS STEINBERGER.
